UNITED STATES PATENT OFFICE.

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

FASTENER-FEEDING MECHANISM.

1,398,346.

Specification of Letters Patent. Patented Nov. 29, 1921.

Original application filed January 23, 1919, Serial No. 272,683. Patent No. 1,364,215, dated January 4, 1921. Divided and this application filed March 3, 1920. Serial No. 362,980.

To all whom it may concern:

Be it known that I, WILLIAM C. STEWART, a subject of the King of England, residing at Swampscott, in the county of Essex and 5 State of Massachusetts, have invented certain Improvements in Fastener-Feeding Mechanisms, of which the following description, in connection with the accompanying drawings, is a specification, like 10 reference characters on the drawings indicating like parts in the several figures.

This invention relates to fastener feeding mechanisms and is herein illustrated by reference to a tacking mechanism designed 15 for use in machines for pulling uppers over lasts in the manufacture of boots and shoes, the present application being a division of my prior application Serial No. 272,683, filed on January 23, 1919, which has matured 20 into Patent 1,364,215, granted Jan. 4, 1921. It is to be understood, however, that the invention is not limited in its applicability to that particular kind of machine nor restricted to the use of fasteners in the form 25 of tacks.

In the use of a tacking mechanism comprising, as in the construction shown, a tack separator and conduits or tubes through which the tacks are conducted to the 30 driving means it sometimes happens that through misplacement of a tack or from some other cause the delivery of tacks to one of more of the tubes is interrupted. When this occurs it is the usual practice to de- 35 tach a portion of the structure affording access to the interior of the separating means, and in order to facilitate dislodgment of any misplaced tacks, as well as to render it more readily apparent when the separator 40 is working properly, it is also the practice to detach some or all of the conducting tubes or parts of such tubes. When this is done, however, tacks sometimes fall from the separating means into the interior of the ma- 45 chine where, if they are permitted to remain, they may interfere with the proper operation of the machine or may cause serious damage. The fact that a tack has thus fallen into the machine may not be noted 50 by the operator, and in any event the difficulty of locating and of removing such a tack, particularly in a complicated machine

like that for pulling over shoes, is a source of annoyance and expense.

An object of this invention is to obviate 55 difficulties such as those above mentioned, and to this and other ends features of the invention reside in novel means affording insurance under such abnormal conditions against the falling of fasteners among the 60 operating parts of a machine. The desired objects are attained in the construction shown by the use of a member arranged to rest normally in an idle position against detachable conducting tubes in such manner 65 that upon detachment of the tubes the member tips automatically into position to receive any tacks that may be discharged from the separator at those points, this member in the illustrative construction acting as a deflector to direct the tacks into a receptacle. In its application to an organization such as shown in which different tubes or groups of 70 tubes are detachable independently, the invention further provides different members 75 independently movable into position to perform the required function.

The above and other features of the invention, including certain details of construction and combinations of parts, will now be 80 more particularly described with reference to the accompanying drawings and pointed out in the claims.

In the drawings:

Figure 1 is a view in side elevation of the 85 upper portion of a pulling-over machine provided with fastening mechanism in which the present invention is incorporated, and

Fig. 2 is a perspective view on an enlarged scale of a portion of the mechanism shown 90 in Fig. 1.

Mounted on the head of the machine is a hopper 48 whereby loose tacks are supplied to tack delivery means comprising a plurality of raceways 50 and a separator 52 which is movable transversely across the lower ends of the raceways and is adapted to support individual tacks and deliver them through discharge openings into conducting tubes 54 which lead to the tack driving mechanism 100 (not shown). The tubes 54 are detachably connected to the lower ends of short delivery tubes 56 rigidly mounted at said discharge openings under the separator slide 52, and

are arranged in groups, comprising in the construction shown two groups of three and an intermediate group of two, the tubes of each group being connected together and detachable as a unit. In order to afford access to the separator in case the latter fails to perform its function properly, there is provided in front of the separator slide a removable end block 58. These parts comprise 10 an organization of a well-known type features of which are more fully shown and described in prior patents, particularly in Patent No. 1,002,422 granted on September 5, 1911 upon an application of R. F. McFeely, 15 to which reference may be made for a more definite understanding of the construction.

For purposes of the present invention there is secured to a portion of the supporting structure a tack receptacle 59 which extends 20 under the tack delivery mechanism at the rear of the conducting tubes 54. Hinged on a rod 60 which is mounted in lugs 62 in the receptacle 59 are chutes or deflectors 64 which are mounted to swing, each independently 25 of the others, and are arranged to rest normally in an idle position against the tubes 54, the construction shown comprising a separate chute for each of the removable groups of tubes. Each of the members 64 is 30 thus constantly in position to be swung, for example by gravity, underneath the lower ends of the corresponding short delivery tubes 56 in the event of detachment of the associated group of conducting tubes 54. 35 Any tack or tacks discharged from the corresponding tubes 56 will thus be caught and deflected into the receptacle 59. In addition to the receptacle 59 there is provided a second receptacle 66 arranged to extend along 40 in front of the tubes 54 in position to catch any tacks which may fall from the front of the delivery mechanism after the block 58 is removed. Between the receptacles 59 and 66 a space is thus provided for the passage of 45 the tubes 54, and the members 64 are arranged to prevent tacks from falling through this space upon their discharge from the tubes 56 when the tubes 54 are detached.

In the use of the mechanism the operator, 50 in the event of failure of delivery of tacks to one or more of the tack drivers, detaches a group or groups of conducting tubes 54 from the delivery tubes 56 and by working the separator 52 back and forth attempts to 55 dislodge any tack which obstructs the proper movement of the separator. Immediately upon removal of a group of tubes 54 the corresponding chute or deflector 64 swings under the ends of the corresponding tubes 56 into 60 position to catch any tacks delivered from the separator through these tubes and thus to prevent any tacks thus discharged from falling into the interior of the machine. If necessary also the end block 58 65 may be removed to afford access to the sepa-

rator, and if this is done the front receptacle 66 serves to catch any tacks that may drop from the front of the mechanism. Effective insurance is thus afforded against damage to the operating parts of the machine and 70 against loss of time in searching for and removing tacks that may have fallen into the machine.

Having described the invention, what I claim as new and desire to secure by Letters 75 Patent of the United States is:

1. In a fastener feeding mechanism, the combination with parts relatively displaceable to assist in clearing the mechanism of misplaced fasteners, of means movable automatically in consequence of such relative displacement of parts of the mechanism into position to receive fasteners released from said mechanism.

2. In a fastener feeding mechanism, the combination with means for separating individual fasteners from a source of supply and for releasing the fasteners, of means movable automatically upon disconnection of parts of the mechanism into position to receive fasteners released from the separating means.

3. In a fastener feeding mechanism, the combination with fastener delivery means, of a conduit for receiving fasteners delivered by said means, said conduit being so mounted as to permit it to be disconnected from the delivery means, and means mounted for movement automatically in consequence of disconnection of the conduit into 100 position to receive fasteners discharged from said delivery means.

4. In a fastener feeding mechanism, the combination with fastener delivery means, of a conduit for receiving fasteners delivered by said means, said conduit being so mounted as to permit it to be displaced from operative position, a receptacle for fasteners, and a chute arranged to rest normally against said conduit and when the conduit 110 is displaced to move into such relation to the delivery means as to direct into said receptacle fasteners discharged from said means.

5. In a fastener feeding mechanism, the combination with fastener delivery means, of a conduit for receiving fasteners delivered by said means, said conduit being so mounted as to permit it to be disconnected from the delivery means, a receptacle for 120 fasteners, and a pivotally mounted chute arranged to rest normally against said conduit and to swing automatically in consequence of disconnection of the conduit into position to direct into said receptacle fasteners discharged from the delivery means.

6. In mechanism of the class described, the combination with fastener separating means and removable tubes for conducting fasteners therefrom, of means arranged to 130

extend under said separating means in front and in back of said tubes for receiving misplaced fasteners while leaving a space between its front and rear portions through 5 which the tubes extend, and a deflector arranged to assume automatically a position such as to prevent fasteners from falling through said space when the tubes are removed.

10 7. In mechanism of the class described, the combination with fastener separating means, short tubes extending downwardly therefrom, and conducting tubes detachably connected to said short tubes, of a receptacle 15 arranged to extend along side of said conducting tubes for receiving fasteners discharged from the separating means, and deflecting means arranged to rest normally against said conducting tubes and to move 20 into position under the ends of the short tubes when the conducting tubes are detached.

8. In mechanism of the class described, the combination with fastener separating 25 means and a plurality of groups of detachable conducting tubes connected to said means, of a receptacle arranged to extend along side of said tubes for receiving tacks discharged from the separating means, and 30 a plurality of deflectors corresponding respectively to the different groups of tubes, each of said deflectors being mounted to swing into position to receive fasteners discharged from the separating means when 35 its group of tubes is detached and to direct such fasteners into the receptacle.

9. In mechanism of the class described, the combination with fastener separating means and a conduit detachably connected to said separating means, of a fastener receiving member arranged to rest normally in an idle position against said conduit below the separating means and automatically movable upon detachment of the conduit into position to intercept fasteners that fall 40 45 from the separating means.

10. In mechanism of the class described, the combination with fastener delivery means provided with a discharge opening, and a detachable conduit for conducting fasteners from said opening, of a member mounted for movement under said opening into position to receive fasteners discharged therefrom when said conduit is detached.

11. In mechanism of the class described, the combination with means for separating individual fasteners from a source of supply and for releasing said fasteners, of a fastener receiving tube extending downwardly from said separating means and displaceable from its operative position, and a member controlled by said tube to move automatically in consequence of such displacement of the tube into a position beneath the point of delivery of the fasteners for intercepting fasteners released from the separating means after the tube has been displaced.

In testimony whereof I have signed my name to this specification.

WILLIAM C. STEWART.
